[57] **ABSTRACT**

This invention relates generally to the machine-processing of scallops and specifically to a means of improving efficiency in the eviscerating process.

SCALLOP MUSCLE AND VISCERA PRECONDITIONER

Prior art machines used in this step accept the muscle with viscera attached immediately following its separation from the shell, and depend upon the eviscerator to perform the complete evisceration step.

One objection to this procedure is that the viscera is often held tightly to the muscle as a result of the heat treatment generally used in the shell-shucking process, and further that one part of the viscera, the roe-sack, in spawning season becomes large and of a flat shape and of a rubbery consistency and is held tightly against the muscle, making it difficult to achieve a high percentage of thoroughly cleaned muscles during their travel through the eviscerator, thus making necessary extensive hand-sorting to separate those not suitable for packing.

The object of this invention is to precondition the muscle and viscera in a separate step, making it more amenable to removal of the viscera by the eviscerator, this occurring between the shucking and eviscerating processes.

In the drawing, I have illustrated one mechanical embodiment of this invention.

FIG. 1 is a section view of one embodiment of this invention which illustrates the sequence of steps in the viscera-preconditioning process at any point along the axis of its one moving part.

Uneviscerated scallops 1 are introduced through a hopper 2 to the space between the cylindrical hollow drum 3 which turns on a horizontal axis 4 in a counter clockwise rotation, directional arrow A, and in close proximity with a circumferential portion of a cylindrical shell 5, of a larger diameter, and on a parallel axis to that of said shell and so located that the space between the shell and drum surfaces is greater at the top and less at the bottom and with a gradually decreasing space from top to bottom. The drum's outer surface 6 and shell's inner surface 7 are textured to prevent the muscle with viscera from slipping on either surface. At the bottom of the shell is attached a chute 8 for exit of the muscle with viscera. A linear spray of water 9 parallel to the drum's axis is applied to the drum surface to assist in removal of any bits of viscera separated from

the muscle.

The muscles with viscera attached 1 and introduced at hopper 2 are rolled under increasing pressure of the gradually narrowed space between the rotating drum surface 6 and shell surface 7 from the top to the bottom where they are released through the exit chute 8. This rolling action under gradually increasing pressure lessens the rigidity of the muscle, loosens the soft portions of the viscera and helps to twist the firm, rubbery, generally wide and flat roe-sack from the muscle, thus preconditioning the muscle with viscera attached for introduction to the eviscerating apparatus.

What is claimed is:

1. In an apparatus for the machine-processing of scallops, or the like, and having the purpose of preconditioning the uneviscerated muscle by softening the rigidity of the muscle, breaking the membrane which jackets the muscle body and loosening the viscera and gonads and which apparatus includes two frictional surfaces with a space between them at one point approximately the same as the diameter of the scallop meat and at another point less than the diameter of the scallop meat and a means of introducing the uneviscerated muscles between said surfaces at the wider opening, and a means of moving at least one of said surfaces in such a manner that the scallop muscle is rotated against the other surface under gradually increasing pressure caused by the narrowing of the space between the two surfaces and a means of releasing the muscle after it has traveled its course.
2. An apparatus constituting one embodiment of the apparatus set forth in claim 1 wherein the two frictional surfaces consist of a cylindrical drum with a coarsely textured outer cylindrical surface turning within a semi-cylindrical shell with coarsely textured inner surface, the axis of the shell being parallel to that of the drum and slightly above it so that the opening between them at the top is greater than at the bottom, the said drum turning in a direction such that its surface within the shell is turning downward, and said means of introducing the uneviscerated scallop meats to these surfaces consisting of a hopper at the top of the cylindrical shell and said means of releasing consisting of a chute at the bottom of the cylindrical shell.
